UNITED STATES PATENT OFFICE.

JOSHUA J. JONES, OF PITTSBURGH, PENNSYLVANIA, ASSIGNOR, BY MESNE ASSIGNMENTS, TO UNION DRAFT GEAR COMPANY, A CORPORATION OF ILLINOIS.

DRAW-GEAR AND BUFFING APPARATUS.

1,072,470.

Specification of Letters Patent.

Patented Sept. 9, 1913.

Application filed December 9, 1908. Serial No. 466,602.

To all whom it may concern:

Be it known that I, JOSHUA J. JONES, a citizen of the United States, residing at Pittsburgh, in the county of Allegheny and State of Pennsylvania, have invented new and useful Improvements in Draw-Gear and Buffing Apparatus, of which the following is a specification.

This invention relates to draw-gear and buffing apparatus, more particularly of that type in which frictional resistance is employed for taking up and absorbing or dissipating shocks produced by draft and buffing in the movements of railway rolling stock.

The principal object of my improvements is to provide an improved construction of the above character which while providing a large area of friction surface is compact, simple in construction, and inexpensive to manufacture.

In the accompanying drawing; Figure 1 is a vertical longitudinal section of a draft gear and buffing apparatus embodying my improvements; and Fig. 2 a top plan view thereof, a part being shown in section.

According to a preferred construction of my invention, the draw-bar shank 1 is provided with oppositely arranged pockets or notches in which are carried the main friction elements consisting of triangular or wedge shaped blocks 3. These friction blocks are provided with oppositely inclined friction faces 2 and 4, the blocks being so disposed that the one set of faces 4 is above the other set of faces 2, or in other words, the friction faces 2 and 4 are disposed on opposite sides of a longitudinal plane. By this means, space longitudinally is greatly economized and a large number of blocks presenting an increased amount of friction surface may thus be employed.

The friction faces 2 coat with corresponding inclined faces of the draw bar pockets, and friction elements 5, also of triangular cross section, are provided and are adapted to bear on the opposite friction faces 4 of the friction blocks 3.

The most forward opposite pair of the blocks 5 bear against a suitable abutment 9 secured to and between the car center sills 10, while the rearmost opposite pair of friction blocks 3 bear against a similar abutment 11.

The friction elements are maintained in

position laterally by plates 6, one above the top row of blocks 5 and one below the bottom row of blocks 5 and one or more coil springs 8, mounted intermediate one of the plates 6 and straps 7 passing around the friction mechanism, serve to resist the lateral movement of the parts. If desired the draw-bar may be constructed with openings 12 in order to reduce the weight thereof.

When a pulling strain is exerted on the draw-bar, the main friction blocks 3 are carried forward with the draw-bar and as the blocks 5 are held again forward longitudinal movement by the abutment 9, it will be apparent that the blocks 5 are forced to ride up on the friction faces 4 of the main friction blocks 3 against the yielding resistance of the springs 8.

In buffing, the draw-bar moves inwardly and in this case the main blocks 3 are held against longitudinal movement by the rear abutment 11, so that the blocks 3 are forced laterally, producing frictional resistance on the faces 2.

It will now be evident that one set of inclined faces 4 of the blocks 3 are in action upon movement of the draw-bar in one direction, while the other set of inclined faces 2 come into play upon movement of the draw-bar in the opposite direction, and that by placing the opposite faces of the blocks 3 abreast instead of in tandem, double the number of blocks may be employed in a given longitudinal space, and the area of friction surface presented is correspondingly increased.

Having now described my invention, what I claim as new and desire to secure by Letters Patent, is:—

1. In a friction draw-gear and buffing apparatus, the combination with a draw-bar, of friction blocks having oppositely inclined friction surfaces arranged one above the other and means adapted to frictionally engage either the upper or the lower inclined surfaces of the friction blocks according to the direction of movement of the draw-bar.

2. In a friction draw-gear and buffing apparatus, the combination with a draw-bar, of friction blocks having inclined friction faces arranged on opposite sides of a longitudinal plane and means for frictionally engaging the friction faces on one side of said longitudinal plane in draft movements and the friction faces on the opposite side

- 2
- of said plane, in buffing movements of the draw-bar.
3. In a friction draw-gear and buffing apparatus, the combination with a draw-bar having inclined friction faces and friction elements having inclined friction faces, of friction blocks provided with friction faces inclined in one direction for engaging the friction faces of the draw-bar and with friction faces inclined in the opposite direction for engaging the friction faces of said friction elements.
4. In a friction draw-gear and buffing apparatus, the combination with a draw-bar having inclined friction faces and friction elements having inclined friction faces, of friction blocks provided with friction faces inclined in one direction for engaging the friction faces of the draw-bar and with friction faces inclined in the opposite direction for engaging the friction faces of said friction elements, and yielding spring means for resisting lateral movement of said friction blocks and elements.
5. In a draft gear and buffing mechanism, the combination with a draw-bar having notches on opposite sides provided with inclined friction faces, laterally movable friction blocks carried in said notches and having inclined friction faces adapted to engage the corresponding friction faces of the notches, friction elements bearing on said friction blocks, and yielding means for resisting lateral movement of said blocks and elements.
6. In a draft gear and buffing mechanism, the combination with a draw-bar having inclined friction faces, of friction blocks carried by said draw-bar and adapted to engage said friction surfaces, friction elements bearing on said blocks to frictionally resist longitudinal movement of the blocks and the draw-bar in one direction, spring means for opposing the movement of said blocks, and a fixed abutment for engaging said blocks upon longitudinal movement of the draw-bar in the opposite direction to thereby effect a relative movement of the blocks upon the inclined friction surfaces and cause a lateral movement of the blocks relative to the draw-bar.
7. In a friction draft gear and buffing apparatus, the combination with a draw-bar, of friction elements and friction blocks having one set of friction faces adapted to act on friction faces of the friction elements upon longitudinal movement of the draw-bar in one direction and another set of friction faces adapted to act on friction faces of the draw-bar upon longitudinal movement of the draw-bar in the opposite direction and spring means for opposing movement of said friction blocks.
- In testimony whereof I have hereunto set my hand.

JOSHUA J. JONES.
